PACKING RETAINER FOR JOURNAL BOXES

John D. Herr, Minerva, Ohio

Application February 28, 1952, Serial No. 273,963

10 Claims. (Cl. 308—89)

1

The invention relates to retainers for packing in journal boxes, and more particularly to a device for retaining waste in the journal box of a railway car.

An object of the invention is to provide a packing retainer which may be inserted into the journal box before the packing or waste is placed therein.

Another object is to provide a packing retainer which may be applied to any conventional type of railway car journal box.

A further object is to provide a packing retainer which is not anchored in any part of the journal box, whereby the retainer is free to move in all directions with the journal and will at the same time prevent the top of the packing from being lodged under the journal bearing.

Another important object of the invention is to provide such a packing retainer having spring means therein to aid in holding the packing into contact with the bottom of the journal at all times and in all conditions of the packing.

A still further object is to provide a packing retainer which will completely prevent lateral movement of the packing and prevent the packing from working out from under the journal.

A further object is to provide a packing retainer in which the portions thereof which are likely to come into contact with the journal at any time are formed of non-abrasive material so as not to produce so-called cold cuts upon the journal such as are caused by conventional types of retainers.

It is also an object of the invention to provide a packing retainer having a hinged front portion which greatly facilitates the placing of the packing in the journal box.

The above objects together with others which will be apparent from the drawing and following description, or which may be later referred to, may be attained by constructing the improved packing retainer in the manner hereinafter described in detail, and illustrated in the accompanying drawings, in which:

Fig. 1 is a detached, perspective view of a packing retainer embodying the invention;

Fig. 2 a vertical, longitudinal sectional view through a journal box, showing the improved packing retainer located therein;

Fig. 3 a transverse, vertical, sectional view through the journal box, taken as on the line 3—3, of Fig. 2; and

Fig. 4 a horizontal, longitudinal, sectional view, taken as on the line 4—4, Figs. 2 and 3.

Referring now to the embodiment of the in-

2

vention illustrated, in which similar numerals refer to similar parts throughout, a conventional type of journal box for railway cars is indicated generally at 10, containing the journal 11, and adapted to be closed by the usual cover 12.

The bearing 13, located in the top of the journal box, supports the journal 11, and the bearing is engaged by the wedge 14 which engages the top of the journal box, all as in usual and well-known practice in the construction of such journal boxes.

The journal extends into the journal box through an opening 15 on the inner side of the journal box, said aperture being provided with any conventional oil seal 16, having a circular opening 17 for engaging the enlarged, cylindrical portion 18 of the journal.

Suitable packing, preferably the customary waste, as indicated at 19, is located in the bottom of the journal box and extends up into engagement with the bottom of the journal and with the sides of the journal to a predetermined point, as is customary in the packing of journal boxes.

The packing 19 preferably terminates adjacent to the outer end of the journal, leaving an open space 20 to serve as a well for excess lubricant, the level of which is indicated at 21. This lubricant is soaked up by the waste, and by capillary attraction it is drawn up into the upper portion of the waste and thus deposited upon the rotating journal 11, keeping the journal lubricated at all times.

The packing retainer embodying the invention is shown detached in Fig. 1, and comprises the front and rear arcuate members 22 and 23 respectively, connected in spaced relation at their lower ends by the central, longitudinal member 24 which is preferably in the form of an upwardly curved steel spring.

The end members 22 and 23 may be formed of sheet steel or similar material and the rear member 23 is preferably rigidly connected to one end of the arcuate spring 24 as by the angular flange 25 to which the adjacent end of the spring is rigidly attached as by welding indicated at 26.

The front arcuate member 22 is preferably hingedly attached to the adjacent end of the spring member 24 having the spaced hinged knuckles 27 located on opposite sides of the elongated hinge knuckle 28 formed at this end of the spring 24, a hinge pin 29 being located through said hinge knuckles.

The upper ends of the rear arcuate member 23 are forwardly bent as at 30 and the horizontal members 31 are rigidly connected thereto as at

32, by welding or the like. These horizontal members may be formed of aluminum or other soft metal, or suitable plastic, or other non-abrasive material which will not scratch or cut the journal if they happen to come into contact therewith.

The free forward ends of the horizontal members 31 are adapted for detachable connection with the upper ends of the front arcuate member 22. For this purpose a slot 33 may be provided in each upper end of the front arcuate member 22, to receive the free end portion of the adjacent horizontal member 31 which is preferably notched, as at 34, for engaging in the upper end of the adjacent slot 33 and holding the parts in locked position, as shown in full lines in Fig. 1.

There is preferably sufficient spring in the material of which the rear arcuate member 23 is formed to spring the forward ends of the horizontal members 31 slightly upward, as shown in broken lines in Fig. 1, when these horizontal members are disconnected from the front arcuate member 22.

In order to place packing in the journal box the packing retainer, as shown in Fig. 1, is first inserted into the journal box, through the opening 35, the cover 12 being of course held open, the free ends of the horizontal members 31 being disconnected from the front arcuate member 22 so that they will extend slightly upward, as shown in broken lines in Fig. 1, and the hinged front arcuate member 22 may be swung forwardly against the bottom of the journal box.

With the packing retainer in this position, the waste 19 is then inserted through the opening 35 of the journal box and packed around the underside of the journal, against the rear arcuate member 23 and against the undersides of the horizontal members 31 of the packing retainer.

When sufficient packing has been properly placed around the underside of the journal, the hinged front arcuate member 22 is then swung upward upon its hinge and detachably connected to the ends of the horizontal members 31, so that the packing is retained as shown in Figs. 2, 3 and 4.

From the above it will be obvious that the packing retainer is not anchored in any part of the journal box, but is free to move in all directions with the journal and will at the same time prevent the top of the packing or waste from moving up around the top of the journal and lodging under the bearing.

It will also be seen that the longitudinal spring member 24 will urge the packing upward into contact with the bottom of the journal at all times and in all conditions of the packing.

Furthermore, it will be obvious that the improved packing retainer will completely prevent lateral movement of the packing and prevent the packing from working out from under the journal.

At all times the packing will be prevented from vertical displacement by means of the horizontal members 31, while the front and rear arcuate members 22 and 23 will prevent horizontal displacement of the packing.

By merely releasing the front arcuate member and lowering it, the packing can be set up and serviced.

This device will prevent easy removal and consequent loss by theft, or carelessness on the part of workmen in foreign or home railroads during servicing operations.

In the foregoing description, certain terms have

been used for brevity, clearness, and understanding, but no unnecessary limitations are to be implied therefrom beyond the requirements of the prior art, because such words are used for descriptive purposes herein and are intended to be broadly construed.

Moreover, the embodiments of the improved construction illustrated and described herein are by way of example, and the scope of the present invention is not limited to the exact details of construction.

Having now described the invention or discovery, the construction, the operation, and use of preferred embodiments thereof, and the advantageous new and useful results obtained thereby; the new and useful constructions, and reasonable mechanical equivalents thereof obvious to those skilled in the art, are set forth in the appended claims.

I claim:

1. A packing retainer for journal boxes comprising flat, transversely disposed front and rear arcuate members to be arranged within the journal box near the opposite ends of the journal for holding packing introduced into the journal box against horizontal displacement, a central longitudinal member connecting the lower portions of the arcuate members, horizontal non-abrasive members connected to the upper ends of the rear arcuate member adapted for arrangement within the journal box on opposite sides of the journal for holding packing against vertical displacement and having detachable connection with the upper ends of the front arcuate member, the horizontal members being adapted for preventing vertical displacement of the packing and the arcuate members being adapted for preventing horizontal displacement of the packing.

2. A packing retainer for journal boxes comprising flat, transversely disposed front and rear arcuate members to be arranged within the journal box near the opposite ends of the journal for holding packing introduced into the journal box against horizontal displacement, a central longitudinal member connecting the lower portions of the arcuate members, horizontal flat spring members connected to the upper ends of the rear arcuate member adapted for arrangement within the journal box on opposite sides of the journal for holding packing against vertical displacement and having detachable connection with the upper ends of the front arcuate member, so that the horizontal members can be moved to raised and lower positions, the horizontal members being adapted for preventing vertical displacement of the packing and the arcuate members being adapted for preventing horizontal displacement of the packing.

3. A packing retainer for journal boxes comprising flat, transversely disposed front and rear arcuate members to be arranged within the journal box near the opposite ends of the journal for holding packing introduced into the journal box against horizontal displacement, a central longitudinal member connecting the lower portions of the arcuate members, horizontal flat spring members connected to the upper ends of the rear arcuate member adapted for arrangement within the journal box on opposite sides of the journal for holding packing against vertical displacement and having detachable connection with the upper ends of the front arcuate member, the horizontal members being adapted for preventing vertical displacement of the packing and the arcuate members being adapted for preventing horizontal displacement of the packing.

members being adapted for preventing horizontal displacement of the packing.

4. A packing retainer for journal boxes comprising front and rear arcuate members to be arranged within the journal box near the opposite ends of the journal, a central longitudinal upwardly curved member connecting the lower portions of the arcuate members, horizontal members connected to the upper ends of the rear arcuate member for arrangement within the journal box on opposite sides of the journal and having detachable connection with the upper ends of the front arcuate member, the horizontal members being adapted for preventing vertical displacement of the packing and the arcuate members being adapted for preventing horizontal displacement of the packing, and the central longitudinal upwardly curved member holding the packing against the bottom of the journal.

5. A packing retainer for journal boxes comprising front and rear arcuate members to be arranged within the journal box near the opposite ends of the journal, a central longitudinal spring member connecting the lower portions of the arcuate members, horizontal members connected to the upper ends of the rear arcuate member for holding packing against vertical displacement on opposite sides of the journal and having detachable connection with the upper ends of the front arcuate member, the horizontal members being adapted for preventing vertical displacement of the packing and the arcuate members being adapted for preventing horizontal displacement of the packing, and the central longitudinal spring member holding the packing against the bottom of the journal.

6. A packing retainer for journal boxes comprising front and rear arcuate members to be arranged within the journal box near the opposite ends of the journal, a central longitudinal member rigidly connected to the lower portion of the rear arcuate member, means hingedly connecting the lower portion of the front arcuate member to said central longitudinal member, horizontal members connected to the upper ends of the rear arcuate member for holding packing against vertical displacement on opposite sides of the journal and having detachable connection with the upper ends of the front arcuate member, the horizontal members being adapted for preventing vertical displacement of the packing and the arcuate members being adapted for preventing horizontal displacement of the packing.

7. A packing retainer for journal boxes comprising front and rear arcuate members to be arranged within the journal box near the opposite ends of the journal, a central longitudinal member rigidly connected to the lower portion of the rear arcuate member, means hingedly connecting the lower portion of the front arcuate member to said central longitudinal member, horizontal flat spring members connected to the upper ends of the rear arcuate member adapted for arrangement within the journal box on opposite sides of the journal and having detachable connection with the upper ends of the front arcuate member, so that the horizontal members can be moved

to raised and lowered positions, the horizontal members being adapted for preventing vertical displacement of the packing and the arcuate members being adapted for preventing horizontal displacement of the packing.

8. A packing retainer for journal boxes comprising front and rear arcuate members to be arranged within the journal box near the opposite ends of the journal, a central longitudinal member rigidly connected to the lower portion of the rear arcuate member, means hingedly connecting the lower portion of the front arcuate member to said central longitudinal member, horizontal flat members connected to the upper ends of the rear arcuate member adapted for arrangement within the journal box on opposite sides of the journal and having detachable connection with the upper ends of the front arcuate member, the horizontal members being adapted for preventing vertical displacement of the packing and the arcuate members being adapted for preventing horizontal displacement of the packing.

9. A packing retainer for journal boxes comprising front and rear arcuate members to be arranged within the journal box near the opposite ends of the journal, a central longitudinal upwardly curved member rigidly connected to the lower portion of the rear arcuate member, means hingedly connecting the lower portion of the front arcuate member to said central longitudinal member, horizontal members connected to the upper ends of the rear arcuate members adapted for arrangement within the journal box on opposite sides of the journal and having detachable connection with the upper ends of the front arcuate member, the horizontal members being adapted for preventing vertical displacement of the packing and the arcuate members being adapted for preventing horizontal displacement of the packing, and the central longitudinal upwardly curved member holding the packing against the bottom of the journal.

10. A packing retainer for journal boxes comprising front and rear arcuate members to be arranged within the journal box near the opposite ends of the journal, a central longitudinal spring member rigidly connected to the lower portion of the rear arcuate member, means hingedly connecting the lower portion of the front arcuate member to said central longitudinal member, horizontal members connected to the upper ends of the rear arcuate member adapted for arrangement within the journal box on opposite sides of the journal and having detachable connection with the upper ends of the front arcuate member, the horizontal members being adapted for preventing vertical displacement of the packing and the arcuate members being adapted for preventing horizontal displacement of the packing, and the central longitudinal spring member holding the packing against the bottom of the journal.
